APPARATUS FOR FEEDING CIGARETTES
AND OTHER ARTICLES OF SIMILAR
SHAPEJohn Walker Chalmers and Arthur Alfred Foale,
Deptford, London, England, assignors to Molins
Machine Company, Limited, London, EnglandApplication January 27, 1937, Serial No. 122,672
In Great Britain February 6, 1936

16 Claims. (Cl. 226—5)

This invention is for improvements in or relating to apparatus for feeding cigarettes and other articles of similar shape and refers to apparatus of the type in which the articles, (for example, cigarettes) are contained in a hopper having an outlet through which the articles pass between spaces provided between partitions. Apparatus of this type will be referred to in the appended description as "apparatus of the type described."

According to one form of the invention there is provided apparatus of the type described wherein the articles in the hopper move down an inclined guide or guides to the outlet, the inclination of the said guide or guides being less steep near the outlet (for example, curved so that the lower portion of the guides are practically horizontal) to retard the speed of the articles, and means operable at intervals alternately to impede and release respectively the articles.

According to a further form of the invention there is provided apparatus of the type described wherein means disposed in the path of the articles is arranged just prior to the articles passing through the outlet of the hopper to align the articles so that the longitudinal axes of the articles are substantially parallel with the faces of the partitions between which the articles are to pass.

According to a further form of the invention there is provided apparatus of the type described wherein the articles are moved towards the outlet from two opposite sides of the hopper, the articles from the two sides being moved towards the outlet at different levels whereby articles from one side are delivered to articles on the other side of the hopper.

According to a still further form of the invention there is provided apparatus of the type described wherein the height of the tops of the partitions varies from one side of the outlet to the opposite side thereof, whereby the tops of the lower partitions are disposed at the bottom of pockets formed between the higher partitions for the purpose of facilitating the passage of the articles between the partitions.

The invention will be described by way of example with reference to the accompanying drawings in which:

Figure 1 is an end elevation of a part of a cigarette packing machine and shows mechanism for feeding cigarettes into the path of a conveyor.

Figure 2 is a side elevation of Figure 1.

Figure 3 shows a part of Figure 1 with some of

the elements in positions different from the positions shown in Figure 1.

Like references refer to like parts throughout the specification and drawings.

For the purpose of describing the invention, the invention is applied to a cigarette packing machine, but it is to be understood that where herein the term "cigarette" is used, it is not used in a limiting sense and other articles of similar shape may be used with apparatus constructed in accordance with the invention.

Referring to the drawings, cigarettes are contained in a hopper 4, the hopper being disposed above the bed 5 of a cigarette packing machine.

An outlet 6 is provided in the bottom of the hopper and the cigarettes pass through the outlet 6 towards partitions 7 between which the cigarettes pass towards the bed 5 of the machine.

Beneath the partitions a succession of pusher pieces 8 carried by an endless, continuously moving conveyor chain 38, are arranged to pass over the bed 5 of the machine; the pusher pieces being provided with slots 9, see Figure 3, so as to pass between the partitions 7, each pusher piece 8 in turn removing a predetermined number of cigarettes from between the partitions. The partitions are arranged so that the cigarettes contained in the spaces between the partitions have their longitudinal axes disposed in the direction of movement of the pusher pieces.

The cigarettes in the hopper 4 move down inclined guides 10 and 11, and from Figure 1 it will be seen that the inclination of the guides is less steep near the outlet 6, the end portions of the guides being curved so that the lower portions of the guides are practically horizontal. By this arrangement the speed of the articles moving down the guides towards the outlet 6 is retarded as the cigarettes are delivered to the opening.

Above the partitions 7 and disposed within the hopper, members 12 and 13 are arranged to co-operate with the guides 10 and 11 and are operable at intervals to impede and release respectively the cigarettes passing down the guides 10 and 11. As shown in the drawings, the members 12 and 13 are secured to a V-plate 14 which is pivoted at 15. The members 12 and 13, together with the guides 10 and 11 form passages through which the articles move towards the outlet of the hopper.

It will be seen that the members 12 and 13 are shaped so that each of the passages converges towards the outlet of the hopper. The members 12 and 13 are oscillated about the pivot 15 by an eccentric 16 which co-operates with a

slot 17 in a block 18 secured to the V-shaped plate 14. The members 12 and 13 are arranged so that the path through which they move is concentric with the curved portions of the guides 10 and 11. The surfaces of the members 12 and 13 which co-operate with the guides 10 and 11 respectively converge towards the guides 10 and 11; it will, therefore, be appreciated that, as a member 12 or 13 moves away from the opening 6, the distance between that member and the guide which co-operates therewith will be increased so that the passage formed between that member and guide is opened and the cigarettes in the passage are released so that they may move more easily towards the outlet 6. The arrangement is such that whilst the cigarettes in the passage formed between the member 12 and its co-operating guide 10 are being released the progress of the cigarettes between the member 13 and its co-operating guide 11 is being impeded.

A substantially inverted V-shaped shroud 19 is arranged above the members 12 and 13 and supports the bulk of the cigarettes in the hopper 4 so as to reduce the pressure of the cigarettes in the passages. The shroud 19 is stationary but is provided with additional supporting surfaces shown as movable extensions 20 and 21, such extensions being pivoted to the shroud at 22 and 23 respectively and controlled by flat springs 24 and 25. The extensions 20 and 21 are arranged still further to relieve the pressure on the cigarettes in the passages when the members 12 and 13 are operated to release the cigarettes in the passages.

As will be seen from Figure 1 of the drawings, the extensions 20 and 21 are provided with tail pieces which protrude through slots in the members 12 and 13 so that in effect these tail pieces form a continuation of the passages. As a member 12 or 13 is moved to release the cigarettes in a passage, a projection 26 carried by the member 12 or 13 engages with the extension 20 or 21 and rotates such extension about its pivot so that the extension is moved away from the outlet 6 and beyond that face of the shroud 19 which supports the cigarettes in the hopper, thereby still further relieving the pressure of the cigarettes in such passage. The extensions 20 and 21 are movable in synchronism with the members 12 and 13 respectively, and as shown in the drawings, the extensions are movable in response to the movement of the members 12 and 13.

In order that the cigarettes shall pass freely between the partitions 7, it is desirable that the longitudinal axes of the cigarettes are substantially parallel with the faces of the partitions between which the cigarettes are to pass, and to improve the arrangement of the cigarettes and the better to align the cigarettes so that their longitudinal axes are substantially parallel with the faces of the partitions 7, some at least of the cigarettes which pass from the passages towards the opening 6 are arrested by an element 27 and are aligned thereby whilst the remaining cigarettes tend to assume the correct position by contact with those cigarettes which are aligned by the element 27. As shown in Figure 1, the element 27 is secured to the block 18 and is movable therewith gently to agitate the cigarettes above the outlet 6 and to facilitate the alignment of the cigarettes.

As an alternative to the element 27 or, if desired, in addition thereto, an outermost partition may be arranged to co-operate with an edge of the outlet of the hopper and project into the

path of the cigarettes moving towards the outlet, the cigarettes moving down the guide towards the outlet being arrested by the projecting partition and aligned by the face thereof.

5 In practice it is sometimes found that when cigarettes are delivered from opposite sides of a hopper the cigarettes from the opposite sides become jammed in a manner such that the free passage of the cigarettes through the outlet towards the partitions is interrupted. For the purpose of reducing this tendency the lower or end portions of the guides 10 and 11 over which the cigarettes pass immediately before passing to the outlet are so arranged that the guide 11 is 10 at a higher level than the guide 10 and since as stated above the ends of the guides are practically horizontal, it will be appreciated that the ends of the guides are in substantially parallel planes.

15 20 The partitions 7 are arranged so that each alternate partition is fixed, whereas, the remaining partitions are movable into and out of the outlet 6 and intersect a line representing the shortest distance between the opposed ends of the guides 10 and 11. Movement is imparted to the partitions by a cam 28 which co-operates with a cam follower 29, secured to a carriage 30 to which the movable partitions are connected, the carriage 30 being slidable on guides 31.

25 30 As can be seen from Figure 3, the top edges of the movable partitions are arranged so as always to lie in a plane different from and above the plane of the top edges of the fixed partitions so that a pocket is formed between adjacent 35 movable partitions and the fixed partitions are arranged in the bottoms of such pockets. When the movable partitions are moved upwardly, as shown in chain line in Figure 3, the dimensions of the pockets are increased, and it will be seen 40 that each pocket is arranged to contain a small number of cigarettes, for example, two or four. By sub-dividing the cigarettes into small quantities such as these, the passage of the cigarettes between the partitions is facilitated.

45 45 As will be seen from Figure 3, one of the movable partitions is provided with a top edge of increased thickness as indicated at 32, the purpose of this increased thickness being to reduce the distance between adjacent movable partitions so that should the distance between the adjacent movable partitions be such as normally to permit two cigarettes to pass therebetween, three badly shaped cigarettes will be prevented from passing between the partitions and becoming jammed therebetween.

50 55 What we claim as our invention and desire to secure by Letters Patent is:

1. In feeding apparatus for elongated articles, the combination with a hopper receiving the articles, said hopper having an outlet in the lower portion thereof, guide means associated with said hopper for supporting said articles and directing the same toward said outlet, said guide means being downwardly inclined toward said outlet, the inclination of said guide means being less steep at points adjacent said outlet than at points more remote therefrom, whereby the rate of movement of said articles is retarded as the latter approach said outlet, and means movable into and out of the path of movement of said articles as the latter leave said guide means to establish a substantially parallel relation of the longitudinal axes of said articles, said last-named means being located at a distance from the discharge end of said guide means which

is less than the smallest cross-sectional dimension of an article.

2. In feeding apparatus for elongated articles, the combination with a hopper receiving the articles, said hopper having an outlet in the lower portion thereof, guide means associated with said hopper for supporting said articles and directing the same toward said outlet, said guide means being downwardly inclined toward said outlet, the inclination of said guide means being less steep at points adjacent said outlet than at points more remote therefrom, whereby the rate of movement of said articles is retarded as the latter approach said outlet, and means movable into and out of the path of movement of said articles as the latter leave said guide means to establish a substantially parallel relation of the longitudinal axes of said articles, said last named means including one of a plurality of partitions disposed below said outlet, said partitions having opposed faces extending generally parallel to the length of said articles as the latter emerge from said outlet, such partition being located at a distance from the discharge end of said guide means, which distance is less than the smallest cross-sectional dimension of an article.

3. In feeding apparatus for elongated articles, the combination with a hopper receiving the articles, said hopper having an outlet in the lower portion thereof, partitions disposed below said outlet, said partitions having opposed faces extending generally parallel to the length of said articles as the latter emerge from said outlet, the upper edges of adjacent partitions being disposed at different levels, whereby passage of the articles therebetween is facilitated, guide means associated with said hopper for supporting said articles and directing the same toward said outlet, said guide means being downwardly inclined toward said outlet, the inclination of said guide means being less steep at points adjacent said outlet than at points more remote therefrom, whereby the rate of movement of said articles is retarded as the latter approach said outlet, one of said partitions being located at a distance from the discharge end of said guide means and movable into and out of the path of movement of said articles as the latter leave said guide means to establish a substantially parallel relation of the longitudinal axes of said articles, the distance by which said partition is removed from the discharge end of said guide means being less than the smallest cross-sectional dimension of an article.

4. In feeding apparatus for elongated articles, the combination with a hopper receiving the articles, said hopper having an outlet in the lower portion thereof, partitions disposed below said outlet, said partitions having opposed faces extending generally parallel to the length of said articles as the latter emerge from said outlet, means for reciprocating certain of said partitions in the direction of the faces thereof toward and away from said outlet, guide means associated with said hopper for supporting said articles and directing the same toward said outlet, said guide means being downwardly inclined toward said outlet, the inclination of said guide means being less steep at points adjacent said outlet than at points more remote therefrom, whereby the rate of movement of said articles is retarded as the latter approach said outlet, one of said partitions being located at a distance from the discharge end of said guide means and movable into and out of the path of movement

of said articles as the latter leave said guide means to establish a substantially parallel relation of the longitudinal axes of said articles, the distance by which said partition is removed from the discharge end of said guide means being less than the smallest cross-sectional dimension of an article.

5. In feeding apparatus for elongated articles, the combination with a hopper receiving the articles, said hopper having an outlet in the lower portion thereof, guide means associated with said hopper for supporting said articles and directing the same toward said outlet, said guide means being downwardly inclined toward said outlet, the inclination of said guide means being less steep at points adjacent said outlet than at points more remote therefrom, whereby the rate of movement of said articles is retarded as the latter approach said outlet, means movable into and out of the path of movement of said articles as the latter leave said guide means to establish a substantially parallel relation of the longitudinal axes of said articles, said last-named means being located at a distance from the discharge end of said guide means which is less than the smallest cross-sectional dimension of an article, and means disposed above said guide means and movable over the latter to facilitate movement of the articles toward said outlet.

6. In feeding apparatus for elongated articles, the combination with a hopper receiving the articles, said hopper having an outlet in the lower portion thereof, partitions disposed below said outlet, said partitions having opposed faces extending generally parallel to the length of said articles as the latter emerge from said outlet, guide means associated with said hopper and disposed at each side of said outlet for supporting said articles and directing the same toward said outlet, the lower end portions of said guide means at opposite sides of said outlet being disposed at different horizontal levels, and means for vertically displacing at least one of said partitions between positions such that the upper edge of the partition lies alternately above and below a straight line drawn between the lower edge portions of the guide means.

7. In feeding apparatus for elongated articles, the combination with a hopper receiving the articles, said hopper having an outlet in the lower portion thereof, guide means associated with said hopper for supporting said articles and directing the same toward said outlet, a stationary surface disposed within the hopper and cooperating with said guide means to support the bulk of the articles in the hopper and to form a restricted throat through which the articles pass in moving toward said outlet, and a member so formed and positioned as to afford a continuation of said stationary surface, said member being supported for movement in a direction generally normal to such stationary surface and away from said outlet to minimize jamming of articles in the throat.

8. In feeding apparatus for elongated articles, the combination with a hopper receiving the articles, said hopper having an outlet in the lower portion thereof, guide means associated with said hopper for supporting said articles and directing the same toward said outlet, a stationary surface disposed within the hopper and cooperating with said guide means to support the bulk of the articles in the hopper and to form a restricted throat through which the articles pass in moving toward said outlet, means for agitat-

ing the articles passing through such throat, said last named means including a member disposed above and movable over the said guide means toward and away from said outlet, and a member so formed and positioned as to afford a continuation of said stationary surface, said last named member being supported for movement in a direction generally normal to such stationary surface and away from said outlet to minimize jamming of articles in the throat. 10

9. In feeding apparatus for elongated articles, the combination with a hopper receiving the articles, said hopper having an outlet in the lower portion thereof, guide means associated with said hopper for supporting said articles and directing the same toward said outlet, a stationary surface disposed within the hopper and co-operating with said guide means to support the bulk of the articles in the hopper and to form a restricted throat through which the articles pass in moving toward said outlet, means for agitating the articles passing through such throat, said last named means including a member disposed above and movable over the said guide means toward and away from said outlet, and a member so formed and positioned as to afford a continuation of said stationary surface, said last named member being supported for movement in a direction generally normal to such stationary surface and away from said outlet to minimize jamming of articles in the throat and being actuated in response to movement of said first named member. 30

10. In feeding apparatus for cigarettes, the combination with a hopper receiving the cigarettes, said hopper being formed to provide in the lower portion thereof an inclined wall terminating adjacent an outlet, a stationary support disposed within said hopper, said support presenting an inclined surface, said wall and surface converging downwardly and having the adjacent portions thereof spaced to afford a throat, whereby the bulk of the cigarettes above said wall and surface are supported thereby, and means movable into and out of the plane of said inclined surface to facilitate passage of cigarettes through said throat, said means including a member constructed and arranged to afford a passage for cigarettes intermediate said throat and said outlet. 40

11. In feeding apparatus for cigarettes, the combination with a hopper receiving the cigarettes, said hopper being formed to provide in the lower portion thereof an inclined wall terminating adjacent an outlet, a stationary support disposed within said hopper, said support presenting an inclined surface, said wall and surface converging downwardly and having the adjacent portions thereof spaced to afford a throat, whereby the bulk of the cigarettes above said wall and surface are supported thereby, and means movable into and out of the plane of said inclined surface to facilitate passage of cigarettes through said throat, said means including a member constructed and arranged to afford a passage for cigarettes intermediate said throat and said outlet converging toward the latter. 60

12. In feeding apparatus for cigarettes, the combination with a hopper receiving the cigarettes, said hopper being formed to provide in the lower portion thereof an inclined wall terminating adjacent an outlet, a stationary support disposed within said hopper, said support presenting an inclined surface, said wall and surface converging downwardly and having the 70

adjacent portions thereof spaced to afford a throat, whereby the bulk of the cigarettes above said wall and surface are supported thereby, means movable into and out of the plane of said inclined surface to facilitate passage of cigarettes through said throat, said means including a member constructed and arranged to afford a passage for cigarettes intermediate said throat and said outlet, and mechanism for reciprocating said member substantially in the direction in which the cigarettes move in passing between said throat and said outlet. 15

13. In feeding apparatus for cigarettes, the combination with a hopper receiving the cigarettes, said hopper being formed to provide in the lower portion thereof an inclined wall terminating adjacent an outlet, a stationary support disposed within said hopper, said support presenting an inclined surface, said wall and surface converging downwardly and having the adjacent portions thereof spaced to afford a throat, whereby the bulk of the cigarettes above said wall and surface are supported thereby, means movable into and out of the plane of said inclined surface to facilitate passage of cigarettes through said throat, said means including a member constructed and arranged to afford a passage for cigarettes between said throat and said outlet and an element supported above said outlet for engaging and moving the cigarettes to agitate the same. 25

14. In feeding apparatus for cigarettes, the combination with a hopper receiving the cigarettes, said hopper being formed to provide in the lower portion thereof an inclined wall terminating adjacent an outlet, a stationary support disposed within said hopper, said support presenting an inclined surface, said wall and surface converging downwardly and having the adjacent portions thereof spaced to afford a throat, whereby the bulk of the cigarettes above said wall and surface are supported thereby, means movable into and out of the plane of said inclined surface to facilitate passage of cigarettes through said throat, said means including a member constructed and arranged to afford a passage for cigarettes between said throat and said outlet, an element supported above said outlet for engaging and moving the cigarettes to agitate the same, and mechanism for moving said means and said element in timed relation. 45

15. In feeding apparatus for elongated articles, the combination with a hopper receiving the articles, said hopper having an outlet in the lower portion thereof, means associated with said hopper for supporting said articles and directing the same toward said outlet, said means affording two inclined stationary surfaces converging toward said outlet, said surfaces being so disposed as to support the bulk of the articles in the hopper and to form a restricted throat through which the articles pass in moving toward said outlet, and means for agitating the articles passing through such throat, said last named means including a smooth surfaced member disposed above and movable over one only of the said surfaces toward and away from said outlet, said smooth surfaced member being mounted for a bodily reciprocatory movement in the direction of flow of the articles passing through the throat. 55

16. In feeding apparatus for elongated articles, the combination with a hopper receiving the articles, said hopper having an outlet in the lower portion thereof, guide means associated

with said hopper for supporting said articles and directing the same toward said outlet, said guide means being downwardly inclined toward said outlet, and means movable into and out of the path of movement of said articles as the latter leave said guide means to establish a substantially parallel relation of the longitudinal axes of said articles, said last named means being

located at a distance from the discharge end of said guide means which is less than the smallest cross-sectional dimension of an article, and means disposed above said guide means and movable over the latter to facilitate movement of the articles toward said outlet.
